BABY BATH SPONGE

Robert J. Arrix, Fort Lee, N.J., assignor to Johnson & Johnson, a corporation of New Jersey

Filed June 22, 1959, Ser. No. 56,458

Term of patent 14 years

(Cl. D9—2)

Fig. 1 is a top plan view of a body bath sponge, showing my new design;

Fig. 2 is a side view; and

Fig. 3 is a sectional view of Fig. 1 taken along lines 3—3.

I claim:

The ornamental design for a baby bath sponge, as shown.
